CARRYING CASE FOR FISHING RODS

Joseph Sabatino, Dayton, Ohio

Application December 29, 1947, Serial No. 794,217

12 Claims. (Cl. 220—23)

1

This invention relates to a carrying case for fishing rods.

One object of the invention is to provide a rod case which is of light weight and easily handled and which has separate compartments for each of a relatively large number of rod sections.

A further object of the invention is to provide a rod case having means for carrying a reel, or other accessories, without materially increasing the size of the case, or interfering with the handling of the case or with access to the rods therein.

A further object of the invention is to provide a rod case having an end closure provided with a reel compartment.

A further object of the invention is to provide such a rod case in which the reel compartment is so protected that there is little or no danger of it being accidentally opened so that the reel may fall therefrom.

Other objects of the invention may appear as the case is described in detail.

In the accompanying drawings Fig. 1 is a perspective view of a rod case embodying the invention; Fig. 2 is a longitudinal sectional view taken on the line 2—2 of Fig. 3; Fig. 3 is a top plan view of a case with the closure in its open position and partly broken away; Fig. 4 is a perspective view of the upper portion of the case showing the upper end section thereof in its open position to permit access to the rods; Fig. 5 is a similar view showing the closure for the upper end section of the case in its open position to permit access to the interior thereof; Fig. 6 is a front elevation of the adjacent end portions of the upper and lower sections of the case, broken away to show the latching mechanism in elevation; Fig. 7 is a fractional section taken on the line 7—7 of Fig. 6; Fig. 8 is a fractional section taken on the line 8—8 of Fig. 6; Fig. 9 is a perspective view of an anti-rattling device; and Fig. 10 is a perspective view of the upper end of a modified form of the case showing the closure therefor in its open position.

In these drawings I have illustrated a preferred embodiment of the invention, together with a minor modification thereof, but it is to be understood that the rod case as a whole as well as the several parts thereof, may take various forms without departing from the spirit of the invention.

The case comprises an elongate body portion 10 open at its upper end and provided with an upper end section 24 movably connected with the open end of the lower or body section and

2

forming a continuation thereof. The terms "upper" and "lower" are herein used with reference to the case when the latter is in an upright position. Both sections of the case are rectangular in form and the body section is divided into a plurality of compartments which for the most part are rectangular in cross section and are of such a character as to utilize all the space within the body of the case. In the arrangement shown 5 in the body of the case is divided by a longitudinal partition 11 into two longitudinal parts. Each of these parts is divided by partitions 12, 13 and 14 into longitudinal compartments of different sizes. As here shown the compartments in the 10 two parts of the case are the same in number and the corresponding compartments in the two parts are of the same size, but obviously the compartments may be of any suitable sizes and of any suitable number. The compartments 15, formed 15 by the respective partitions 12 and the front wall 16 of the case, are relatively large and each is adapted to receive the handle portion of a casting rod. The handles of casting rods are usually 20 relatively large and are provided with projections or finger pieces extending from one side thereof, to provide a firm hand grip. Usually casting rod handles when mounted in a case do not have any part of the rod connected therewith and are therefore relatively short. For 25 the purpose of supporting such a handle in the upper portion of either compartment 15 each of these compartments is provided with a supporting device, such as a cross bar 17, spaced from the upper end thereof and arranged to be engaged 30 by the finger piece on the handle and thus support the handle in the upper portion of the compartment. The finger piece is of narrow width and occupies but a small part of the width of the compartment and in order to utilize this space, a 35 longitudinal partition 18 extends diagonally across the outer corner of each of the compartments to form in said corner a subcompartment 19 triangular in form. If desired a hook or knob 40 may be attached to the partition 18 to support an accessory, such as a device for stringing fish. The compartments 20, formed between the partitions 12 and 13, are somewhat smaller than the compartments 15 and are adapted to receive the handle section of a fly rod, such a handle 45 usually having a rod section secured thereto. The compartments 21, formed by the partitions 14 and 11, are relatively small and these compartments, as well as the compartments 19, are adapted to receive sections of a rod, or rod tips. 50 55 The case is provided with a suitable handle for

carrying the same and as here shown, the handle, 22, is connected with the front wall of the body portion substantially midway between the ends of the case as a whole so that the latter will be substantially balanced when supported by the handle. It may also be desirable to provide in the lower portions of the several compartments cushioning devices 23, such as pads of felt or the like, to protect the rod sections if they should be permitted to drop into the compartments for substantially their entire length.

The movable upper end section 24 of the case is of substantial length and is hollow and adapted to provide space in which reels or other accessories may be carried. It is here shown as having its back wall connected with the back wall of the body section by hinges 25, the abutting walls of the two sections being rabbeted, as shown at 26, to provide a tight joint between the two sections and to hold the same against relative lateral displacement. The lower end of the upper section, that is the end adjacent the body section, is closed by a wall 27 and is provided with a movable closure to permit access to be had thereto. In the present instance this closure is shown at 28 as the front wall of the end section and is hinged to the top wall thereof at 29. The interior of the end section 24 is divided by a partition 30 into two compartments each of which is large enough to receive a reel and/or other accessories. It is, of course, necessary to provide means for securing the end section 24 in closing relation to the open upper end of the body section and it is also desirable that the closure 28 for the end section, or reel compartments, shall be secured in its closed position and that the closure 28 shall be retained in its closed position both when the end section is secured in closing relation to the body section and when it is in opening relation to the body section, so as to avoid the possibility of the reels, or other accessories, from falling from the compartments when the end section is moved to its open position. For this purpose I have provided suitable latching means for securing the end section in closing relation to the body section and for securing the compartment closure of the end section in its closed position. In the present arrangement a single latching device is used for this purpose and is of such a character that the locking of the end section in line with the body section will also lock the compartment closure in closing position, and that the compartment closure must be locked before the end section can be moved to its open position. In the arrangement shown the body section is provided on the inner side of the upper end of its front wall 16 with a keeper 31, and the end section 24 is provided adjacent the front edge of one of its side walls with a keeper 32. The latching device further comprises two latching members 33 and 34 connected one with the other and in the present instance forming parts of a single latching element 35 which is rigidly secured to the inner end of a pin 36 rotatably mounted in the lower portion of the compartment closure 28 and having rigidly secured to its outer end an actuating device or knob 37. The keeper 31 on the body portion is of substantial length transversely of the body and has an arcuate lower edge 38. The latching member 33 is provided at its outer end with a forwardly extending lip 39 adapted to be moved into engagement with the arcuate edge of the keeper 31 by the rotation of the element 35. The latching member 34 has a flat end portion adapted to be

moved into retaining engagement with the keeper 32 on the wall of the case by the rotation of the element 35. When the latching member 33 is moved into locking engagement with the keeper 31 the latching member 34 will be out of engagement with its keeper 32 but the latching member being mounted on the inner side of the compartment closure 28 its engagement with the keeper 31 will not only lock the end section in closing relation to the body section but will lock the closure 28 in closing relation to the compartments within the end section. When the latching member 33 is moved out of engagement with the keeper 31 the end of the latching member 34 will be moved into retaining engagement with the keeper 32 and the relative positions of the two latching members, and the lengths of the two keepers are such that the latching member 34 will engage the keeper 32 before the latching member 33 is moved entirely out of engagement with the keeper 31. Consequently the releasing of the end section for movement to its open position automatically locks the compartment closure in its closed position. Preferably the latching member 33 is of resilient material and is provided with a forwardly extending rounded projection 40 adapted to enter a recess in the keeper 31 when the latching member is in proper locking relation thereto and thus yieldably retain the latching member in that position. Thus it will be apparent that the reel compartments can be opened only after the end section or body closure has been moved to its open position and the latching device actuated to release the closure 28.

The rod sections are, of course, of relatively small diameter with relation to their respective compartments and in order to prevent the same from rattling when the case is being carried I have provided an anti-rattling device, preferably in the nature of a flat plate 41 of suitable material, as shown in Fig. 9. This plate is adapted to fit in the upper portion of the body section and to rest upon the partitions therein and is of such dimensions that it will have little or no movement transversely to the body. It is provided with openings 42 through which the ends of the rods may extend, it being understood, of course, that the anti-rattling device is placed about the rods after the latter have been inserted in their compartments.

In Fig. 10 I have shown a slightly modified form of the invention in which the body section 43 is similar in shape to the body section 10 above described but in which the arrangement of the partitions 44 is somewhat different from that above described. The closure 45 for this form of the case is hinged to the upper end of the body portion thereof as shown at 46 and is provided with flanges 47 to engage the upper ends of the walls of the body, but it is not provided with compartments and is not particularly adapted to serve as a container.

While I have shown and described one embodiment of my invention I wish it to be understood that I do not desire to be limited to the details thereof as various modifications may occur to a person skilled in the art.

Having now fully described my invention what I claim as new and desire to secure by Letters Patent is:

1. A carrying case for fishing rods comprising an elongate body section open at one end and adapted to receive sections of a fishing rod, a relatively short end section having therein a

compartment and an opening through which fishing accessories may be inserted in and removed from said compartment, a closure for said opening, means for mounting said closure on said end section for movement into and out of a position to close said opening, means for mounting said end section on said body section for movement into and out of a position to close the open end of said body section, means for retaining said end section in said closing position, and means controlled by said retaining means to retain the closure for said compartment in its closed position.

2. A carrying case for fishing rods comprising an elongate body section open at one end and adapted to receive sections of a fishing rod, a relatively short end section having therein a compartment and an opening through which fishing accessories may be inserted in and removed from said compartment, a closure for said opening, means for mounting said closure on said end section for movement into and out of a position to close said opening, means for mounting said end section on said body section for movement into and out of a position to close the open end of said body section, a latching device having means for retaining said end section in closing relation to said body section and for retaining said compartment closure in its closed position while said end section is in closing relation to said body section, and means cooperating with said latching device for retaining said compartment closure in closed position after said end section has been released for movement to body opening position.

3. A carrying case for fishing rods comprising an elongate body section open at one end and adapted to receive sections of a fishing rod, a relatively short end section having therein a compartment and an opening through which fishing accessories may be inserted in and removed from said compartment, a closure for said opening, means for mounting said closure on said end section for movement into and out of a position to close said opening, means for mounting said end section on said body section for movement into and out of a position to close the open end of said body section, a latching mechanism having means for locking said compartment closure to said body section and thereby retaining both said compartment closure and said end section in closing positions, and having other means for retaining said compartment closure in closing position when it has been released from said body section.

4. A carrying case for fishing rods comprising an elongate body section open at one end and adapted to receive sections of a fishing rod, a relatively short end section having therein a compartment and an opening through which fishing accessories may be inserted in and removed from said compartment, a closure for said opening, means for mounting said closure on said end section for movement into and out of a position to close said opening, means for mounting said end section on said body section for movement into and out of a position to close the open end of said body section, a latching mechanism having means for locking said compartment closure to said body section and thereby retaining both said compartment closure and said end section in closing positions, and having other means for retaining said compartment closure in closing position when it has been released from said body section, and a single device operable

from the exterior of said case for actuating both of said retaining means.

5. A carrying case for fishing rods comprising an elongate body section open at one end and adapted to receive sections of a fishing rod, a relatively short end section having therein a compartment and an opening through which fishing accessories may be inserted in and removed from said compartment, a closure for said opening, means for mounting said closure on said end section for movement into and out of a position to close said opening, means for mounting said end section on said body section for movement into and out of a position to close the open end of said body section, a keeper on said body section, a second keeper on a part of said end section other than said closure, a latching member movably mounted on said compartment closure to engage the keeper on said body section and retain said end section in closing position with relation to said body section and to retain said closure in closing position with relation to said compartment, a second movable latching member on said closure to engage said second keeper and retain said closure in compartment closing position when the first mentioned latching member has been moved out of engagement with its keeper, and a single device for actuating both latching members.
- 15 6. A carrying case for fishing rods comprising an elongate body section open at one end and adapted to receive sections of a fishing rod, an end section, means for mounting said end section on said body section for movement to and from a position to close the open end of said body section, said end section having a compartment therein and a movable wall forming a closure for said compartment, separate keepers on said body section and on a part of said end section other than said movable wall, latching members mounted on said movable wall for movement into or out of engagement with the respective keepers, and single device for actuating both latching members.
- 20 7. A carrying case for fishing rods comprising an elongate body section open at one end and adapted to receive sections of a fishing rod, an end section, means for mounting said end section on said body section for movement to and from a position to close the open end of said body section, said end section having a compartment therein and a movable wall forming a closure for said compartment, separate keepers on said body section and on a part of said end section other than said movable wall, a latching device movably supported on the inner side of said movable wall, having part to engage one of said keepers when said device is moved to one position, and having a second part to engage the other of said keepers when said device is moved to a second position, and means supported on the outer side of said movable wall for operating said device.
- 25 8. A carrying case for fishing rods comprising an elongate body section open at one end and adapted to receive sections of a fishing rod, an end section, means for mounting said end section on said body section for movement to and from a position to close the open end of said body section, said end section having a compartment therein and a movable wall forming a closure for said compartment, separate keepers on said body section and on a part of said end section other than said movable wall, a latching device rotatably supported on the inner side of said movable wall and having two members rigid therewith

and adapted to engage the respective keepers, said members being so positioned with relation one to the other and to said keepers that the rotation of said device in either direction will move one of said members into engagement with its keeper and will move the other of said members out of engagement with its keeper, and means on the outer side of said movable wall for rotating said device.

9. A carrying case for fishing rods comprising an elongate body section open at one end and adapted to receive sections of a fishing rod, an end section, means for mounting said end section on said body section for movement to and from a position to close the open end of said body section, said end section having a compartment therein and a movable wall forming a closure for said compartment, separate keepers on said body section and on a part of said end section other than said movable wall, a latching device movably supported on the inner side of said movable wall and having separate parts to engage the respective keepers, said parts being so positioned with relation one to the other and to said keepers that the operation of said device to engage one of said parts with its keeper will disengage the other of said parts from its keeper before the first mentioned part has been engaged with its keeper, and means supported on the outer side of said movable wall for operating said device.

10. A carrying case for fishing rods comprising an elongate body rectangular in cross section and open at one end, partitions dividing said body into a plurality of longitudinal compartments rectangular in cross section, and of different sizes adapted respectively to receive handle and rod sections of fishing rods, an end section rectangular in cross section, hinged to the open end of said body section and constituting a closure thereof, said end section having a compartment therein and having its front wall hinged thereto to form a movable closure for said compartment, a keeper on said body section adjacent the open end thereof, a second keeper on a fixed side wall of said end section, a latching device movably supported on the inner side of said hinged wall of said end section and having separate parts to engage the respective keepers, said parts of said latching device being so positioned with relation one to the other and to said keepers that the operation of said device to move one part thereof out of engagement with the keeper on said body section will move the other part of said latching device into engagement with the keeper on said end section before said end section has been released for movement with relation to said body section, and means supported on the outer side of said movable wall of said end section for operating said latching device.

11. A carrying case for fishing rods comprising an elongate body rectangular in cross section and open at one end, partitions dividing said body into a plurality of longitudinal compartments rectangular in cross section and of different sizes adapted respectively to receive handle and rod sections of fishing rods, an end section rectangular in cross section, hinged to the open end of said body section and constituting a closure thereof, said end section having a compartment therein and having its front wall hinged thereto

7
8
to form a movable closure for said compartment, a keeper on said body section adjacent the open end thereof, a second keeper on a fixed side wall of said end section, a latching device movably supported on the inner side of said hinged wall of said end section, said latching device having a part to engage the keeper on said body section when said latching device is moved to one position and thereby retain said front wall of said end section against movement with relation to either said body section or said end section, and also having a second part to engage the keeper on said end section when said latching device is moved out of engagement with the keeper on said body portion and thereby retain said front wall of said end section in compartment closing position when said end section is released for movement with relation to said body section, and means operable from the exterior of said casing to actuate said latching device.

12. A latching mechanism having locking means for both the closure of a main compartment and the closure of an auxiliary compartment, each compartment having an opening coverable by the closure thereof, said auxiliary compartment acting as the closure member of the main compartment, said locking means including a latch member movably mounted on the closure of the auxiliary compartment, said latch member having a plurality of positions, means cooperating with said latch member for locking the closure of the auxiliary compartment and the auxiliary compartment to the main compartment covering the opening of the main compartment when the latch member is in one position, thereby retaining both compartments in closed position, the latch member when actuated to a second position releasing the auxiliary compartment from the main compartment, means cooperating with the latch member when in the second position for retaining the closure for said auxiliary compartment in closed position as the auxiliary compartment is released from the main compartment, the latch member when again moved releasing the closure of the auxiliary compartment.
